US00D890740S

(12) **United States Design Patent** (10) **Patent No.:** **US D890,740 S**
Khubani et al. (45) **Date of Patent:** **** Jul. 21, 2020**

(54) **APPLIANCE HOLDER**(71) Applicant: **DaVinci II CSJ, LLC**, Fairfield, NJ (US)(72) Inventors: **Ajit Khubani**, Saddle River, NJ (US); **Paul Dowd**, Scarsdale, NY (US)(73) Assignee: **DaVinci II CSJ, LLC**, Fairfield, NJ (US)(**) Term: **15 Years**(21) Appl. No.: **29/721,171**(22) Filed: **Jan. 17, 2020**(51) LOC (12) Cl. **14-03**

(52) U.S. Cl.

Primary Examiner — Janice Hallmark(74) *Attorney, Agent, or Firm* — Cooper & Dunham LLP(57) **CLAIM**

The ornamental design for an appliance holder, as shown and described.

DESCRIPTION

FIG. 1 is a downward, front perspective view of an appliance holder in accordance with the present design;

FIG. 2 is an upward perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
